PISTOL GRIP WIRE STRIPPER

Dean Oehlerking, Sycamore, Ill., assignor to Ideal Industries, Inc., Sycamore, Ill., a corporation of Delaware

Filed Oct. 1, 1962, Ser. No. 227,308

11 Claims. (Cl. 81—9.5)

This invention relates to a pistol grip type precision wire stripper.

One purpose of the invention is a wire stripper of the type described in which the wire grippers remove the slug of insulation.

Another purpose is a wire stripper insuring accuracy of alignment and stripping at nominal cost.

Another purpose is a wire stripper which removes the slug of insulation in a direction generally parallel to the stripper frame.

Another purpose is a wire stripper which permits the wire to be removed from the blades without any chance of damaging the stripped end of the wire.

Another purpose is a wire stripper of the type described utilizing a pivotal trigger, with the trigger pivot point shifting during operation.

Other purposes will appear in the ensuing specification, drawings and claims.

The invention is illustrated diagrammatically in the following drawings wherein:

FIGURE 1 is a side view of the stripper,

FIGURE 2 is an orthographic exploded view of a portion of the stripper frame illustrating the grippers and stripper blades,

FIGURE 3 is an enlarged view with the cover removed and portions broken away, of the stripper,

FIGURE 4 is an enlarged view, similar to FIGURE 3, showing the stripper in a closed or stripping position,

FIGURE 5 is a section along plane 5—5 of FIGURE 3,

FIGURE 6 is a section along plane 6—6 of FIGURE 3,

FIGURE 7 is a section along plane 7—7 of FIGURE 3,

FIGURE 8 is a section along plane 8—8 of FIGURE 7,

FIGURE 9 is a section along plane 9—9 of FIGURE 3, and

FIGURE 10 is a section along plane 10—10 of FIGURE 9.

The stripper may include a frame indicated generally at 10 having a pistol grip type handle 12 at one end. The opposite end of the frame 10 may mount a trough indicated generally at 14, and shown particularly in FIGURE 2. Positioned for slideable movement within the trough 14 is a slide 16 having a lower axially or longitudinally extending runner 18 which is positioned in a groove 20 in the bottom of the trough 14.

The slide 16 may have a transverse or laterally extending groove 22 which receives a rear mounting member 23 of what may be termed the gripper 24. In practice, both grippers will move with slide 16. To close the grippers, movable gripper 26, which also has a mounting member in groove 22, moves toward the stationary gripper 24. A coil spring 25 may be used to hold the grippers apart or in an open position. Gripper 24 may have a lower runner 28 in alignment with runner 18 on the slide 16 so that the grippers may be properly aligned when they move in the trough 14.

Mounted at the outward end of the trough 14 is a pair of stripper blades 30, with the right-hand blade, as illustrated in FIGURES 2 and 9, being stationary, and the left-hand blade being movable. A coil spring 31 may hold the blades apart or in the open position. The blades 30 may be fixed to the trough 14 by means of a suitable pin or the like 32.

2

Both the grippers and the stripper blades may be conventional. There will be holes indicated at 34 in FIGURE 9 and at 36 in FIGURE 7, with the size of the holes varying for different sizes of wire. The exact shape and configuration of the grippers and stripper blades form no part of the present invention.

Movable within a side groove 38 in the trough 14 and within a similar side groove 40 in gripper 26 is a push rod 42, having a beveled or chamfered end 44. As the push rod moves toward the grippers and the stripper blades, the beveled end 44 will move the grippers and stripper blades to the closed position.

As illustrated in FIGURES 3 and 4, the end of the push rod 42 opposite the beveled end 44 may be pivotally connected to a trigger 46, as at 48. A spring or the like 50 may be connected to this end of the push rod and to the frame, to urge the push rod 42 away from the grippers and stripper blades.

Connected to the slide 16 is a pull rod 52, which may be screw-threaded into the slide, and which may be encircled by a coil spring 54. This spring is seated, at one end, against a bracket or the like 56, forming a part of the slide 16, and is seated against a stationary spring seat 58 at the other end. The pull rod 52 extends through an opening 60 in the spring seat 58 and has a suitable knob or the like 62 at its far rear end, as illustrated in FIGURES 3 and 4.

The trigger 46 is pivoted to the push rod 42, at its upper end, as described before. A link 64 is pivoted to the trigger 46 at a point spaced from the pivot point 48, with the link 64 being pivoted at its opposite end to a curved lever 66. The lower end of the curved lever 66 is pivoted to the handle, as at 68. The upper end of the curved lever 66 has a yoke 70 which rises on opposite sides of the pull rod 52 and has a projection or the like 72 at one side. The projection 72 will ride along the upper surface 74 of a latch member 76 as the yoke, lever 66 and pull rod are moved toward the rear. The latch 76 is biased, by a spring 80, in the upward direction in FIGURE 3 and is moved to the latched position of FIGURE 4 as the yoke and pull rod move toward the rear. The rear end of the latch 76 has a notch 82 which receives the projection 72 when the pull rod and yoke are in the far right position of FIGURE 4. The projection 72 will snap into the notch 82 and the latch will move up and hold the pull rod in this position and prevent the pull rod from moving forward or toward the left. The latch 76 has a somewhat curved projection 84, at the end away from the notch 82, which is positioned to be contacted by the upper end of the trigger as the trigger is released.

The stripper is completed by a rectangular projection 86 mounted within the handle which supports the latch member 76 and so aligns the latch member as it is moved toward the rear of the stripper.

The use, operation and function of the invention are as follows:

A wire to be stripped is inserted into the frame or barrel in such a manner that the end to be stripped is suitably positioned in a proper sized opening in the grippers and stripper blades. The trigger 46 is then pulled or moved toward the handle. As the trigger is closed it will pivot about the connection between the link 64 and the trigger. The push rod 42 will be driven toward the left, as shown in FIGURE 3, and the beveled end 44 will close the grippers and the stripper blades against the action of the springs normally holding them in the open position.

As soon as the push rod has closed the grippers and the stripper blades, the pivot point for the trigger 46 will shift up to pivot point 48 or the connection between the

trigger and the push rod. The push rod is now stationary. After the pivot of the trigger has shifted, further inward movement of the trigger will move link 64 inward which in turn will move lever 66 in a clockwise direction about its pivot point 68. The yoke 70 at the end of the lever 66 will move the pull rod to the right as shown in FIGURE 3. As the pull rod moves to the right it will pull the grippers and the slide 16 in the trough 14. The insulation has already been cut by the stripper blades. The grippers are removing the slug of insulation by pulling it off the end of the wire. In many prior strippers the blades remove the slug of insulation. In this case it is the grippers that remove the insulation. The lever 66 will continue its pivotal movement and will continue moving the pull rod until the projection 72 on the yoke 70 has moved down into the notch 82 at the end of latch 76. Normally the latch 76 is biased in an upward direction by spring 80. When the latch has been operated, the stripping operation has been completed and the slug of insulation has been removed.

When the trigger is released it will first pivot about the connection with link 64 and the push rod will be moved toward the right. The spring 50 will draw the push rod back and as the push rod moves the blades 30 will be opened. The stripped wire may now be removed. As the trigger pivots about this point, it will contact the end 84 of the latch and will move the latch in a clockwise direction. The notch 82 will be driven down below the projection 72 and will release the pull rod. The spring 54 will then draw the pull rod to the left, as shown in FIGURE 3, and move the grippers back to their original position. As the grippers move back, they will be released as they pass by the beveled end 44 of the push rod. It is necessary to hold the grippers back away from the wire until it has been removed from the stripper. Otherwise it would be possible for the grippers to damage the stripped end of the wire.

Of importance in the invention is the use of the trough and slide for guiding the grippers in the removal of the insulation slug. The grippers remain properly aligned during removal of the slug and there is no chance of bending or scraping the stripped end of the wire.

Another important feature is the shifting pivot of the trigger. This permits a two-step operation in which the first step is the closing of the grippers and the stripper blades and the second step is the movement of the grippers in a direction parallel to the wire to carry off the stripped slug of insulation.

The invention is advantageous for precision stripping. Because the gripper removes the slug of insulation there will be no chance of nicking the wire by the blades. Furthermore, the grippers are removed in a straight line which keeps the wire from being bent. The stripper blades themselves merely close to cut the insulation and then open to permit removal of the wire.

Whereas the preferred form of the invention has been shown and described herein, it should be realized that there are many modifications, substitutions and alterations thereto within the scope of the following claims.

I claim:

1. A wire stripper including a frame, a pistol grip type handle at one end of said frame, a trigger pivoted to said frame adjacent the handle, a pair of stripper blades mounted on said frame at the end away from the handle, a trough mounted on said frame, a pair of grippers mounted in said trough for slideable movement toward and away from said stripper blades, a push rod mounted in said frame for slideable movement toward said stripper blades and grippers, said push rod having a portion positioned to contact said stripper blades and grippers to close them, said push rod being pivotally connected to said trigger, and means, operable by the trigger, for moving the grippers, when closed, in said trough away from the stripper blades to remove the insulation.

2. The structure of claim 1 further characterized in that said trigger pivots on said frame at one position while moving the stripper blades and grippers to a closed position, and pivots at a second position on said frame when moving said grippers away from the stripper blades.

3. The structure of claim 1 further characterized in that the means for moving said grippers in the trough include a pull rod fixed to the grippers and arranged for slideable movement in the frame.

4. The structure of claim 3 further characterized by a yoke pivoted to said trigger and in contact with said pull rod, said yoke being effective to move said pull rod in response to pivotal movement of the trigger.

5. The structure of claim 4 further characterized in that said yoke is positioned within said pistol grip type handle.

6. The structure of claim 3 further characterized by and including a spring encircling said pull rod and urging said grippers in a direction toward said stripper blades.

7. The structure of claim 3 further characterized by and including a latch, pivoted to said handle, for holding said pull rod and gripper blades in position away from said stripper blades until the stripper blades have been opened by release of said trigger.

8. The structure of claim 7 further characterized by a yoke within said handle and pivoted to said trigger, said yoke being effective to move said pull rod and grippers in a direction away from the stripper blades, a portion of said yoke being in contact with said latch whereby the latch holds the yoke, pull rod and grippers away from said stripper blades.

9. A wire stripper including a frame, a pistol grip type handle at one end of said frame, a trigger pivoted to said frame adjacent the handle, a pair of stripper blades mounted on said frame at the end away from the handle, one of said blades being fixed and the other being movable, a trough mounted on said frame, a pair of grippers mounted in said trough for slideable movement toward and away from said stripper blades, one of said grippers being movable toward the other, a push rod mounted in said frame for slideable movement toward said stripper blades and grippers, said push rod having a portion positioned to contact said movable stripper blade and the gripper movable toward the other to close said stripper blades and grippers, said push rod being pivotally connected to said trigger, and means, connected to the trigger, for moving the grippers, when closed, in said trough, away from the stripper blades to remove the insulation from the wire to be stripped.

10. The structure of claim 9 further characterized by and including a spring connected to said push rod and normally urging said push rod away from said stripper blades and grippers.

11. The structure of claim 9 further characterized by spring means normally urging said stripper blades and grippers to the open position.
